UNITED STATES PATENT OFFICE.

FRANK B. LA MAY, OF ROCHESTER, NEW YORK, ASSIGNOR TO CALDWELL MANUFACTURING COMPANY, OF ROCHESTER, NEW YORK, A CORPORATION OF NEW YORK.

MANICURE IMPLEMENT.

SPECIFICATION forming part of Letters Patent No. 775,568, dated November 22, 1904.

Application filed October 3, 1904. Serial No. 226,908. (No model.)

To all whom it may concern:

Be it known that I, FRANK B. LA MAY, of Rochester, in the county of Monroe and State of New York, have invented certain new and useful Improvements in Manicuring Implements; and I do hereby declare the following to be a full, clear, and exact description of the same, reference being had to the accompanying drawings, forming a part of this specification, and to the reference-numerals marked thereon.

My present invention relates to improvements in that class of devices that are particularly useful in trimming, filing, cleaning, and performing similar operations upon the finger and toe nails of a person; and it is the object of my invention to provide a device of this character that will perform these operations in the simplest and most convenient manner and which is capable of being manipulated and handled with the greatest facility without impairing the usefulness of the device.

To these and other ends my invention consists in certain improvements and combinations of parts that will be hereinafter more fully explained, the novel features being pointed out particularly in the claims hereunto annexed.

In the drawings, Figure 1 is a view, partly in section, showing a nail-trimming device embodying my invention, the operating-lever being in operative position. Fig. 2 is a similar view showing the operating-lever and the jaws in their relatively closed positions. Fig. 3 is a view of the device in elevation, the operating-lever being in an intermediate position; and Fig. 4 is a similar view showing the operating-lever in a reversed position. Figs. 5 and 6 are top and bottom plan views, respectively, of the device; and Fig. 7 is a sectional view through the connecting link or pin on the line xx of Fig. 4.

In the several views the same numerals of reference designate similar parts.

The present embodiment of my invention comprises generally the opposing jaws 1 and 2, which are composed in the present instance of a pair of plates which are preferably made of resilient material and are united at one end

by the pins or rivets 3 3, a handle 4 being provided, if desirable, for the purpose of facilitating the manipulation of the device. The opposite ends of these jaws are formed to receive the nail preparatory to the trimming operation, and for this purpose the jaw 2 is provided with the curved or recessed portion 55 5, which conforms approximately to the curvature of the finger-tips, and the opposing jaw 1 is also provided with a similarly-formed recess 6, either or both of the jaws being provided with a cutting edge 7, which is formed 60 to coöperate with the opposing jaw and preferably has a curvature of such a configuration as will enable the nail to be readily trimmed into the desired shape. These jaws 1 and 2 are each provided with the perforations 8 and 9, respectively, the aperture 9 of the jaw 2 being provided with a countersunk recess 10, which is preferably formed oblong, rectangular, or otherwise angularly shaped, and in this countersunk recess is adapted to fit the correspondingly-shaped head 11 of the pin or link 12, the 70 stem of the latter extending through the apertures 8 and 9 of the jaws 1 and 2, respectively, and terminating in a curved or hooked portion 13. This curved or hooked portion 75 of the pin or link is adapted to coöperate with an operating member 14, which in the present instance is forked at one end in such a manner as to admit the said hooked portion of the pin, a pivot 15 being provided between 80 the forks for engaging beneath the said hooked portion of the pin, that portion of the operating member in proximity to the said pivot being disposed at an oblique angle to the body of the member in order that the extremities of the latter will constitute a relatively laterally arranged projection at one side of the said pivot 15, and the bent portion 16 will constitute a similar projection upon the opposite side of the said pivot, such an arrangement 85 causing the projection 16 to bear against the adjacent jaw 1, and thereby move the latter toward the opposing jaw 2, when the free end of the operating member is manipulated toward the device from a position similar to 95 that shown in Fig. 1, thus causing the sharp-

ened cutting edge to sever that portion of the nail which it may be desirable to have removed, the jaws and the operating-lever at this time occupying a position similar to that 5 shown in Fig. 2. When the operation of severing the nails has been completed, the operating member may be thrown over into the position shown in Fig. 3 in order that the file or roughened portion 17 and the pointed im- 10 plement 18, which are preferably formed upon the operating member, may be rendered convenient and accessible for use, the jaws or body portion of the device at this time serving as a handle during this operation. By 15 swinging the operating lever or member 14 about the pin 12 as a center until it assumes a position similar to that shown in Figs. 4 and 5 the device will occupy a comparatively small compass or space that will enable it to be 20 conveniently carried upon the person, and while the operating-lever occupies such a position the extremity of the said lever adjacent to the pin will be so disposed relatively to the pivot 15 of the lever that the resiliency or 25 spring action of the jaws 1 and 2 will operate to retain the operating member closed or in immediate proximity thereto.

For the purpose of preventing the connecting-pin 12 from turning accidentally or too 30 easily and in order to insure the proper positioning of the operating member I provide the angularly-shaped countersunk recess in which the correspondingly-shaped head upon the pin 12 rests, and as the jaws 1 and 2 are 35 preferably so fitted together that their resili- 40 ent action normally tends to separate them it will be readily understood that the pressure thus produced will operate to retain the angularly-shaped head of the pin in such a position within the recess as to normally resist the turning of the pin; but when sufficient force is exerted upon the pin by manipulating the operating-lever 14 the pressure exerted 45 between the head of the pin and the jaws will be overcome, thus permitting the pin to be rotated into its reversed position, in which position it will be retained by the seating of the angularly-shaped head of the pin within the correspondingly-shaped portion of the recess. 50 A device of the character described is particularly useful and convenient as an implement for trimming and dressing the finger and toe nails of a person, and it is so constructed as to simplify and facilitate the ma- 55 nipulation and operation of the device, and in practice the handle 4 may be employed to enable the device to be conveniently and steadily held or grasped by the hand of the operator, the handle being preferably omitted, 60 as in Figs. 2, 3, and 4, when it is desirable to render the device capable of being conveniently carried in the pocket or other small receptacle or space.

I claim as my invention—

65 1. In a device of the character described, the

combination with the coöperative jaws having a normal tendency to separate, and a link or connection mounted in pivotal relation with the jaws, of an operating member coöperating with the said link and having a projection 70 thereon for proximating the said jaws when the said member is operated in one direction, and an oppositely-arranged projection capable of being coöperatively arranged between the said jaws and link when the latter and the 75 operating member are in a relatively reversed position to cause the separating action of the jaws to retain the said member in its closed position.

2. In a device of the character described, the 80 combination with the coöperatively-arranged jaws, and a link or connection mounted in rev- oluble relation with the said jaws, of an op- erating member having a pivotal connection 85 with the said link and provided with oppo- sitely-arranged projections one of which is capable of coöperating with the said link and jaws to proximate the latter when the oper- ating member occupies a predetermined po- 90 sition, the other projection being arranged to coöperate with one of the jaws when the relative positions of the link and operating mem- ber are in a reversed position and thereby re- 95 tain the said member in its closed position.

3. In a device of the character described, the 95 combination with the coöperatively-arranged jaws having a normal tendency to separate, of a pin or link connecting said jaws having an angularly-shaped head thereon arranged to coöperate with a correspondingly-formed re- 100 cess in one of the jaws to resist the rotation of the link, and an operating member coöperating with said link while the latter occu- 105 pies a predetermined position to proximate the jaws, and having a projection thereon op- erating under the separating action of the jaws to retain the operating member in a closed po- 110 sition while the link and operating member oc- 115 cupy relatively reversed positions.

4. In a device of the character described, the 110 combination with the coöperatively-arranged jaws, and the connecting link or pin attached to one of the jaws and having a curved or hooked portion in proximity to the opposite jaw, of an operating member having a pivotal 115 connection with the hooked portion of the pin and provided with a projection arranged to co- 120 operate with one of the jaws to proximate the latter when the operating member is manip- 125 ulated, while in one position and an oppositely- arranged projection formed to coöperate with the said jaw when the connecting-link has been rotated and the operating member is manip- 130 ulated from a relatively reversed position.

5. In a device of the character described, the 125 combination with the opposing jaws formed to receive a finger-nail or the like between them, and having a normal tendency to separate, and a connecting-link rotatably mounted rel- 130 atively to said jaws and having an angularly-

shaped head thereon formed to fit a correspondingly-shaped recess in one of the jaws, of an operating member coöperating with the said link while the latter occupies a predetermined position to proximate the jaws, and operating under the separating action of the jaws when the link is rotated into a reversed position to remain in a closed position in proximity to the adjacent jaw.

10 6. In a device of the character described, the combination with the coöperatively-arranged jaws, and the connecting-link, of an operating member mounted in pivotal relation with said link and having a projection thereon arranged to coöperate with the adjacent jaw to proximate the jaws when the said member is manipulated in one direction, and an angularly-disposed portion arranged to engage the said jaw when the said member is manipulated in

15 the opposite direction and thereby retain the

said member in a predetermined position relatively to the remainder of the device.

7. In a device of the character described, the combination with the coöperatively-arranged jaws, and the connecting-link between them, 25 of an operating member pivotally attached to said link and provided with an angularly-disposed portion forming a projection for engaging one of the jaws for proximating the latter when the said member is manipulated 30 in one direction, and an oppositely-arranged projection upon said angularly-disposed portion and coöperating with the said jaw when the position of the said member is reversed to retain the latter in immediate proximity to 35 the body of the device.
